UNITED STATES PATENT OFFICE.

HERMAN P. ANDRESEN, OF CHICAGO, ILLINOIS, ASSIGNOR OF ONE-HALF TO DAVID J. EVANS, OF CHICAGO, ILLINOIS.

TRAVELING BRIDGE OR CRANE.

No. 903,806.

Specification of Letters Patent. Patented Nov. 10, 1908.

Application filed November 7, 1907, Serial No. 401,131. Renewed October 9, 1908. Serial No. 456,948.

To all whom it may concern:

Be it known that I, HERMAN P. ANDRESEN, a citizen of the United States, and resident of Chicago, Cook county, Illinois, have invented a certain new, useful, and Improved Traveling Bridge or Crane, of which the following is a full, clear, and exact description, such as will enable others skilled in the art to which it appertains to make and use the same.

My invention relates to improvements in apparatus for moving heavy bulk materials, such as ore, coal, stone and the like and has particular reference to improvements in traveling bridges and gauntrees for transfer and storage yards, docks and shops where such materials or other heavy objects are handled.

The object of my invention is to improve the construction and operation of transfer bridges and cranes of the class mentioned with a view to at once facilitating and lessening the cost of handling bulk materials.

My invention will be more readily understood by reference to the accompanying drawings forming part of this specification and in which—

Figure 1 is a longitudinal side elevation of a traveling bridge embodying my invention, the form selected for illustration being that which is best adapted for use upon stock or storage docks or yards, where the bridge travels over the tops of the stock piles; Fig. 2 is an end view of the bridge, shown in Fig. 1; Fig. 3 is a plan view thereof, the dotted lines representing the bridge in two extreme positions; Fig. 4 is an enlarged sectional detail of the rigid tower of the bridge and the car or truck on which it rests, showing also the turn table which is interposed between the tower and the car; Fig. 5 is a horizontal section on the line X—X of Fig. 4; Fig. 6 is an enlarged sectional detail of the pivotal or compensating tower of the bridge and its supporting car, clearly showing the pivots by which the tower is attached to the car and the turn table which is interposed between the upper end of the tower and the bridge proper; Fig. 7 is a horizontal section on the line Y—Y of Fig. 6; and Fig. 8 is a perspective view of the compensating tower and car.

Referring to the drawings A represents the surface of the transfer or storage dock or yard. This surface is usually from three to eight hundred feet in width and of as

great length as found necessary. The tracks, B and C, are parallel and extend from end to end of the yard or dock. The spaces between the tracks and at the sides thereof receive the coal, ore or other material which is formed into long parallel piles commonly referred to as stock piles, D—D. The height of the stock piles is determined by the height of the bridge or elevated structure and as will appear hereinafter an increase in the height of the stock piles is one of the incidents or results of my invention. On each track B—C I arrange a strong car or truck, E—F. These carry the bridge and each car is equipped with a suitable motor for propelling it on its track. Aside from the cars or trucks my bridge comprises three main members, namely the bridge proper, G, and the two towers, H and I, the latter resting upon respective cars E and F.

The bridge proper, G, may be considered as a single beam or girder supported by the towers, H and I, and carrying the trolley, J, from which the grab bucket, K, is suspended. The normal position of the bridge is that in which it is at right angles to the tracks B and C, but it is not limited to operation in this position or relation; instead it is adapted to be moved into various angular positions with respect to the tracks as indicated in Fig. 3. This is accomplished by moving one of the carrying cars or trucks ahead or in advance of the other. The movement of the bridge out of right angled position with respect to the tracks obviously increases the distance between the cars or trucks E and F, changing the relations between the cars and the bridge proper. It is therefore impossible to use towers which would rigidly connect the bridge and the cars; first because such rigid connections would prevent turning or angular movement of the bridge with respect to the cars and tracks; and second because the cars being on parallel tracks would not be permitted to move toward or from each other as is required to advance or retard one with respect to the other. Therefore with a view to allowing maximum freedom of movement and adjustment, I employ one rigid tower and one pivotal or compensating tower. The rigid tower, H, is framed into the bridge structure and prevents longitudinal movement of the bridge. The other tower, I, is in the nature of a vertical link or strut

which is pivoted to the bottom of the bridge and to the top of the car, F, or otherwise, in such manner as to permit the car to move back and forth beneath the upper pivotal point of the tower, *i. e.* beneath the bridge.

The twisting or turning of the bridge with relation to the cars is permitted by a vertical pivot or turn table which I interpose between each of the cars and the bridge. In 10 the case of the rigid tower I preferably arrange the turn table between the car, E, and the lower end of the tower, whereas, the lower end of the compensating tower is pivoted on the car, a long pivot or hinge extending longitudinally of the car being used, and the necessary vertical pivot or turn table is arranged between the upper end of the compensating tower, I, and the bridge. The tower H, therefore, is adapted to turn 15 upon its vertical axis and with respect to the car which supports it, whereas the tower, I, is free to swing or sway upon its car, and does not turn about a vertical axis thereon; but the bridge is free to turn upon the upper 20 end of the pivotal or compensating tower and is thus permitted to assume any desired relation to this non-turning compensating tower. In this connection I desire to call 25 attention to the fact that the upper end of the compensating tower, I, may be pivoted at any desired height on the sides of the bridge, provided the vertical pivot or turn table is arranged at its lower instead of upper end. These modifications and all 30 modifications and combinations incidental thereto may be carried out without in any way departing from the spirit of my invention.

It will be noted that the top of my bridge 35 is straight and that the trolley, J, is mounted on the top or top chord thereof with the bucket hanging at the side of the bridge. The advantage which attaches to this construction is that the bucket may be hoisted above the lower chord of the bridge. It follows that the bucket may be moved from end 40 to end of the bridge while thus suspended and it is not necessary to allow clearance for the passage of the bucket over the tops of the stock piles. The bucket may be dumped 45 or opened while in its highest position and therefore the stock piles may reach practically to the lower chord of the bridge, the only clearance necessary being enough to permit the free movement of the bridge 50 along the tops of the stock piles. The conveyer or traveling bridges hitherto constructed by others have been characterized by chords and trusses rising above the trolley and the grab bucket. A bridge of my 55 construction adapted to pile the material to the same height is therefore much lower and more stable. Reversely, my bridge when made of the same height as other bridges 60 permits the stock to be piled to greater heights. A further special advantage of my

bridge is that the points at which it is supported do not vary but remain constant for all positions of the bridge and cars. At one end it is supported by the rigid tower which does not vary its position, and at the other 70 end it is supported by a pivot bearing, which is also fixed; in other words the bridge span is constant for all positions of the cars or trucks; hence the dead load strains of the bridge proper are constant. The towers are 75 therefore constructed to sustain constant vertical dead load reaction, and as it is unnecessary to design either bridge or tower to take loads for minimum and maximum length of span, the whole structure is of 80 considerably less weight than other structures of the same dimensions and capacity.

A still further advantage of my invention resides in the fact that the bridge is a substantially solid structure. The trolley and 85 grab bucket do not travel between or through any of the trusses or chords as in other bridges, but instead are exterior to the structure making it possible to effectively tie and brace the same throughout, as well shown in 90 the drawings. A narrower bridge results and as shown in the drawings I am able to dispense with the usual floor beams and 95 stringers or hangers for the trolley rails and place the latter directly upon the top chords of the bridge.

Referring to the drawings for further details of construction it will be seen that the bridge portion of my novel apparatus is a simple truss or beam of considerably greater 100 height than width. It is composed of the straight upper members, 1-1, constituting the top chords of the bridge and the bottom members, 2-2, which join the ends of the top chords and constitute the bottom chords 105 of the bridge. These chords are united by vertical, horizontal and diagonal members, 3-3, making a very rigid structure. The rails, 4-4, for the trolley, J, are fastened upon the tops of the chords, 1-1. The 110 towers are of a size determined by the height of the stock piles which are to be formed.

The rigid tower, H, is triangular in side elevation and is rectangular in end elevation. As before stated its vertical members are 115 framed into the bridge. The pairs of side members may be braced as indicated in Fig. 1 and the parallel members at opposite sides are braced by suitable diagonal members, 5-5, as partially shown in Fig. 4.

6 represents the lower member of the rigid tower and on this I secure the vertical pivot pin 7 of the turn table. Turn table members, 8 and 9, are arranged on the tower and the car, and rolls, 10, between them, lessen the friction or resistance to the turning of the tower on the car.

The tilting of the tower on the car is prevented by the side rollers or out riggers, 11-11, journaled in suitable brackets on the 120

members 6, and adapted to roll over the curved ways, 12-12 provided on the top of the car, E. The turn table may be made in various ways well known to mechanics, but I prefer the arrangement shown in Figs. 4 and 5 in which the base of the tower is limited to substantially a single line of contact with the car an arrangement which insures the stability of the tower thereon. It should also be understood that the designs of the turn tables used in my bridge vary according to the weight of the structure. In comparatively light bridges the load may be carried by the outrigger rollers, whereas in heavy structures it is sometimes necessary to distribute the load upon all members of the turn tables. For sake of clearness the turn table is here shown as being considerably above the top of the car or truck, but in practice I arrange the tower bearings as low as possible. My purpose in thus arranging the bearing upon the car is to transform the longitudinal thrust of the bridge into a minimum overturning moment. By so doing it is obvious that stability is insured as the weight of the bridge acting through its arm is amply sufficient to prevent the overturning of the car.

As before stated the turn table at the opposite end of the bridge may be at the lower end of the tower, I, but I prefer to hinge or pivot said lower end upon the truck, F; as shown in Figs. 6 and 8, (see pivot pins 13-13). The hinge pins 13, prevent the turning of the tower, I, on the car. The tower, I, is preferably diamond shaped in side elevation and presents rectangular panels in end elevation (see Figs. 6 and 8). The middle section of the tower is strengthened by the horizontal members, 14-14, and the entire structure is effectively held against torsion or other distortion by a plurality of cross bars, 15 and 16. At top and bottom the side frames are tied together by cross girders or beams, 17-17. It will be observed that fittings, 18-18, at the upper end of the tower provide journals for the end trunnions of the yoke, 19, which carries the center bearing, 20, of the turn table. These fittings also carry the conical rolls or outriggers, 21.

22 represents the cross girder or bearer; constituting part of the bridge and carrying the complementary center bearing, 23, in which the pivot or center pin, 24, is arranged. The center bearing has anti-friction rolls, 25, as shown in Fig. 6. Curved plates, 26, provided on the bottoms of the lower chords of the bridge rest upon the anti-friction rolls, 21-21, and prevent the tipping of the bridge on the column or tower, I. It will be obvious that the yoke, 19, being permitted to turn in the bearings or fittings, 18, conforms to the plane of the bottom of the bridge and is relieved from tor-

sional strains due to the swaying of the tower beneath the bridge. As in the case of the tower, H, and car, E, I prefer to arrange the pivot pins, 13, at low points within the body of the car, instead of upon the top of the car as herein shown.

The trolley, J, is provided with brackets, J', for the sheaves, J'', which overhang the side of the bridge (see Fig. 2). The bucket, K, is suspended from these sheaves. The winding drums and motor, 27, overhang the opposite sides of the bridge to balance the bucket and thereby equalize the loads on the two trusses of the bridge. The operator's cage, J³, may also be suspended at the side of the bridge.

The principal characteristics and features of my invention may be briefly enumerated as follows: 1st. The straight upper chord of the bridge and freedom from frames or members which extend above the trolley track. It will be noted that the trolley operator has an unobstructed view from his position on the trolley and consequent freedom in the operation of the bridge, trolley and grab bucket. 2nd. The arrangement of the trolley rails upon the top chords of the bridge, affording a wide spread for the trolley wheels and also obviating the use of stringers and floor beams between the chords. 3rd. The play or movement of the trolley is only limited by the length of the bridge, it being possible to run the trolley to the extreme end thereof. 4th. The solid and rigid construction of the bridge and towers, as compared with other bridges in which the trolley rails are arranged beneath the upper chords and between the lower chords. 5th. The relative narrowness of the bridge, resulting in reduction of weight and cost. 6th. The ability to hoist and operate the grab bucket above the lower chord of the bridge, which permits the forming of high stock piles. 7th. The simplicity of the anti-friction tower bearings or turn tables. 8th. The ability to move to angular positions and the side range of movement which is possible. 9th. The effectiveness with which the torsional strains are cared for in the towers of the bridge. 10th. Freedom from variation of dead load strains by the relative movement of the cars and trucks, the latter being freely movable without altering the span of the bridge trusses. 11th. The rigidity of the towers, made possible by the fact that they do not serve as arches through which the trolley and grab bucket must operate, but are wholly independent thereof and may be treated as solids. 12th. The relative low height of the bridge and its consequent stability and ability to resist wind pressure and other forces which tend to overturn it.

It is obvious that the bridge herein illustrated may be readily adapted for use as a

gauntree crane. In such cases the cantaliver ends of the bridge may be dispensed with. These and many other modifications of my invention will readily suggest themselves to one skilled in the art and I therefore do not confine the invention to the specific structure herein shown and described.

Having thus described my invention, I claim as new and desire to secure by Letters Patent:

- 10 1. The improvements herein described comprising a bridge proper having a trolley track upon its top, chordal portions in combination with a trolley equipped with hoisting mechanism and adapted to run upon said track and a grab bucket or the like suspended and operable from said trolley at the side of the bridge, substantially as described.
- 15 2. The improvements herein described comprising a bridge having straight top chords, in combination with trolley rails thereon, a trolley to run on said rails and sheaves provided on the trolley and projecting beyond the side of the bridge, substantially as described.
- 20 3. The improvements herein described comprising a bridge proper, in combination with supporting cars for said bridge, one of said cars permitting the bridge to swing in a horizontal plane, compensating means interposed between the other car and the bridge, a trolley track on the top of said bridge and a trolley thereon, substantially as described.
- 25 4. The improvements herein described comprising a bridge proper, in combination with supporting cars for said bridge, a rigid tower, a vertical pivot therefor on one of said cars, a compensating tower interposed between the bridge and the other car, a swivel connection between compensating tower and bridge and a trolley on said bridge, substantially as described.
- 30 5. The improvements herein described comprising a bridge proper in combination with a trolley to operate upon the top of said bridge, supporting cars and tracks therefor, a tower upon each said car, a turn table interposed between each car and the bridge, one of said towers being rigidly joined to the bridge and the other being pivotally connected thereto, substantially as described.
- 35 6. The improvements herein described comprising tracks and cars in combination with an elevated structure carried by said cars and comprising a horizontal portion or bridge proper, a rigid tower adapted for rotation upon a vertical axis on one of said cars and a compensating tower pivotally connecting the other car and said bridge, a turn table being interposed between each car and said bridge, as and for the purpose

70 7. The improvements herein described comprising a pair of supporting cars in combination with a bridge proper, a rigid tower connecting the bridge and one of the cars, said tower being adapted to turn upon its vertical axis, a link-like compensating tower arranged between the other car and said bridge, the latter tower being hinged or pivoted upon its car and a swivel being provided between its upper end and said bridge, substantially as described.

75 8. The improvements herein described comprising a bridge proper which is composed of a pair of upper chords and a pair of lower chords rigidly joined throughout by a plurality of vertical, horizontal and diagonal members, in combination with supporting towers for said bridge, cars whereon the towers are mounted, a trolley adapted to run upon the top of the bridge, and a grab bucket or the like suspended therefrom at the side of the bridge, substantially as described.

80 9. The improvements herein described comprising tracks, cars or trucks on said tracks, a bridge carried by said cars and adapted for angular movement upon and with the cars, said bridge being composed of a pair of side frames or trusses, a trolley adapted to operate upon the top chords of said bridge, and a grab bucket or the like suspended from the trolley at the side of the bridge, substantially as described.

85 10. The improvements herein described comprising a bridge proper in combination with a tower framed into the bridge, a car, a turn table interposed between the lower end of said tower and said car, a second car, a compensating tower which transmits torsion without distortion and whereby the bridge and the second car are pivotally joined as by a link, and a turn table interposed in such manner as to permit relative rotation of the bridge and car upon a vertical axis, substantially as described.

90 11. The improvements herein described comprising a bridge proper, a rigid tower and a compensating tower together supporting the bridge, a trolley movable from end to end of the bridge, and cars whereon said towers rest, substantially as described.

95 12. The improvements herein described comprising a bridge proper in combination with torsion resisting towers, one of which is rigidly connected to the bridge and the other pivoted thereto, and cars supporting said towers and therewith the bridge, substantially as described.

100 13. The improvements herein described comprising a bridge in combination with a tower and car supporting one end thereof, a second car and rigid tower or column whereby the other end of the bridge is supported upon the second car, said rigid tower or column pivotally connecting said second

70

130

car and said bridge after the manner of a link, and means permitting the relative rotation of the bridge and cars, as and for the purpose set forth.

5 14. The improvements herein described comprising parallel tracks and cars thereon, in combination with a bridge extending across said tracks, towers carried by the cars and supporting the bridge, one of said 10 towers being a rigid structure adapted to turn upon its vertical axis, the other being a rigid structure pivoted upon the second car, and a swivel turn table whereby the upper end of the second tower is connected 15 with the bridge, substantially as described.

15. The improvements herein described comprising a bridge having suitably connected top and bottom chords, in combination with a trolley mounted upon the top 20 chords of the bridge, a grab bucket or the like suspended from the trolley at the side of the bridge and adapted to be hoisted above the lower chords thereof, tracks, and cars or trucks mounted thereon and supporting 25 said bridge, substantially as described.

16. The improvements herein described comprising a bridge, in combination with towers and cars whereby the bridge is supported and made movable, a trolley operable 30 upon the top of the bridge, a grab bucket suspended from one side of the trolley, and the bucket operating mechanism arranged at the opposite side of the trolley, substantially as described.

35 17. The improvements herein described comprising a bridge, in combination with a tower and a turn table, supporting one end thereof, a car beneath the other end of the bridge, a compensating tower supporting the 40 bridge upon said car and pivoted to both the tower and the bridge, substantially as described.

18. In a bridge or crane, a bridge and a car beneath the same, in combination with 45 a single pivotal strut or link mounted on said car and movably supporting the bridge above the car, substantially as described.

19. In a bridge or crane, a bridge and a car beneath the same, in combination with a 50 single strut or link occupying a substantially upright position and having its lower end horizontally pivoted upon said car and a combined turn table and horizontal pivot joining the upper end of the strut or link 55 to the bridge, substantially as described.

20. The improvements herein described comprising a bridge, in combination with a tower supporting one end thereof, a car 60 whereon the tower is supported, a pivot permitting relative rotation to the bridge and the car, a second car beneath the other end of the bridge, a tower rigid within itself 65 interposed between the second car and the bridge and pivotally connected with both bridge and pivotally connected with both longitudi-

nal and swinging movements of the bridge over the second car, substantially as described.

21. The improvements herein described comprising a bridge proper, in combination with towers supporting the same, cars supporting the towers and vertical pivots interposed between one of the cars and the bridge to permit the bridge to turn with respect to the car, horizontal pivots or hinge joints joining the ends of the other tower 75 to the bridge and car respectively, and a turn table incorporated with one of said horizontal pivots whereby the bridge is permitted to move longitudinally over the second car and also turn with relation thereto, 80 substantially as described.

22. The improvements herein described comprising a structure movable on parallel tracks and composed of a bridge, supporting towers, cars whereon the towers are mounted, 85 one of said towers being rigidly joined to the bridge and the other tower being connected to the bridge and its car by horizontal hinge joints, substantially as described.

23. The improvements herein described comprising a structure movable on parallel tracks and composed of a bridge, supporting towers, cars whereon the towers are mounted, one of said towers being rigidly joined to the bridge and vertically pivoted upon its 95 car and the other tower being connected to the bridge and its car by horizontal pivots and a vertical pivot, substantially as described.

24. The improvements herein described comprising a bridge composed of parallel trusses and lateral members connecting them throughout, in combination with towers located intermediate of the ends of the bridge and supporting the bridge, cars whereon said towers are mounted for movement upon parallel tracks, the upper chords of said bridge being straight, a trolley located upon the top of the bridge and adapted to move from end to end thereof, said trolley projecting laterally beyond the vertical plane of the sides of the bridge and towers and adapted to convey a weight along the side of the bridge, substantially as described.

110 25. The improvements herein described comprising a bridge having straight top chords, in combination with trolley rails on said chords, a trolley to run on said rails and projecting laterally beyond the side of the bridge and towers arranged beneath and supporting the bridge at points intermediate the ends thereof, substantially as described.

115 26. The improvements herein described comprising a bridge having top chords which are straight from end to end, in combination with a trolley to run upon the top of the bridge and projecting laterally beyond the side thereof, hoisting mechanism on the trolley, a grab bucket or the like suspended from the projecting portion of the trolley, 120

125

130

towers supporting the bridge at intermediate points, and of substantially the same width as the bridge to permit the passage of the bucket at the side thereof, and cars 5 whereon said towers are mounted, substantially as described.

27. The improvements herein described comprising a movable conveyer bridge or structure composed of two parallel trusses 10 connected by cross ties and struts throughout, in combination with trolley rails upon the top chords of said trusses, a trolley movable on said rails, propelling and hoisting mechanisms on said trolley, hoisting sheaves upon 15 said trolley, said sheaves projecting beyond the outer side of one of said trusses, *i. e.*, the side of the bridge, and a bucket suspended from said sheaves, substantially as described.

28. The improvements herein described comprising a bridge proper, in combination 20 with conveying means thereon; supporting cars and tracks, a tower upon each said car, a turn table interposed between each car and the bridge, one of said towers being rigidly joined to the bridge and the other being 25 pivotally connected thereto, substantially as described.

In testimony whereof, I have hereunto set my hand, this 2d day of November, 1907, in the presence of two subscribing witnesses. 30

HERMAN P. ANDRESEN.
